UNITED STATES PATENT OFFICE.

ETHELBERT S. GRIFFITH, OF TOLEDO, OHIO.

FOLDING CHAIR.

SPECIFICATION forming part of Letters Patent No. 244,360, dated July 12, 1881.

Application filed March 1, 1881. (No model.)

To all whom it may concern:

Be it known that I, ETHELBERT S. GRIFFITH, of Toledo, in the county of Lucas and State of Ohio, have invented certain new and useful Improvements in Folding Cot-Chairs, 5 of which the following is a specification.

The objects of my invention are to provide a means for folding the chair into a small and compact parcel for convenience in transportation; and a further object is to provide a 10 means of adjusting the back of the chair to any desired angle or inclination and quickly securing the same firmly in position, and to provide an adjustable, detachable, flexible covering, forming the back and seat thereof, as 15 hereinafter more fully described and set forth.

Figure 1 is a perspective view of a folding cot-chair constructed according to my invention. Fig. 2 is a plan view of the same when 20 folded in one direction. Fig. 3 is a similar view of the same when nearly folded together in the opposite direction.

A represents the back frame or standards, their lower portions serving as the front legs, 25 B, when the chair is in use. To these standards A B are pivoted the legs C, which form the rear legs, and are provided at their upper ends with dowels or tenons e, which fit in corresponding holes formed in the removable 30 cross-piece D forming the front of the seat, and to which is permanently secured the flexible canvas bottom and back W at one end, and the opposite or top end to the cross-piece D', as shown in dotted lines, Fig. 1, this cross- 35 piece D' being also detachable from the upper ends of said back standards A, which are provided with dowels or tenons C, which fit corresponding holes provided in the said cross-piece D', as shown, thus permitting the removal of said cross-pieces D D' and flexible 40 covering W when desired to fold the chair, as shown. Now, in order to permit the said back to be adjusted and secured at any angle of inclination desired, I provide adjustable supports E, which are pivoted at their lower ends 45 at or near the lower ends of the said pivoted cross-legs C, and their upper ends are provided with screw-bolts and thumb-nuts F, said screw-bolts passing through said supports E and the

longitudinal slots G formed in the said back 50 frame-standards A, or by means of the strips or cleats H, secured to the rear of said standards A at their lower ends by a bolt or rivet passing through the same and through the 55 lower ends of the diagonal braces I and the back frame or standards A, the upper ends of the said diagonal braces I being pivoted to the jointed horizontal cross-bars J at points intermediate between the central pivot of said jointed cross-bars J and the back standards 60 A, to which the outer ends of said horizontal cross-bars J are pivoted, as shown.

Now, in order to stay the pivoted cross-legs C, I provide an exact or similar means, consisting of the diagonal braces K, which are 65 pivoted at their lower ends to the said cross-legs C near their lower ends, and at their upper ends to the horizontal jointed cross-bar L intermediate between its center pivot or joint and its outer ends, which are pivoted to the 70 said cross-legs C near their upper ends, as shown.

It will be evident that one or both of the said horizontal jointed cross-bars J and L may be pivoted to either the said back standards A 75 or the cross-legs C at or near the points to which the said diagonal braces I or K are connected or pivoted at their lower ends, thereby reversing the same without departing from my invention, as the same folding results would 80 thereby be accomplished by substantially the same means; therefore I have omitted to illustrate such modification in the figures shown in the drawings.

It will be understood that in order to fold 85 my said cot-chair the said cross-pieces D and D' are to be removed from the dowels e and e, as shown in Fig. 1, which act carries with them the flexible covering W, and then the pivoted cross-legs C are folded inwardly or 90 between the back standards A B, as shown in Fig. 2, by loosening the said thumb-screws F, which permit the bolts to slide downward in said slots G; then, by forcing the said horizontal cross-bars J and L upward or off their 95 centers, the said back standards A B and cross-legs C, with their said diagonal braces I and K, will permit the same to fold into a position

nearly parallel therewith, as shown in Fig. 3, wherein it is not fully closed together, but nearly so.

Having thus described my invention, what I claim is—

A folding cot-chair provided with cross-legs pivoted together in pairs, horizontal jointed braces connecting the pairs of one side with those of the other, and diagonal braces pivoted at one end to the legs and at the other to

the jointed braces, all the parts combined and arranged to operate as set forth.

In testimony that I claim the foregoing I have hereunto set my hand this 10th day of January, 1881.

ETHELBERT S. GRIFFITH.
